UNITED STATES PATENT OFFICE.

CHRISTEN CHRISTENSEN, OF CHICAGO, ILLINOIS, ASSIGNOR TO ELECTRICAL ENGINEERS EQUIPMENT CO., OF CHICAGO, ILLINOIS, A CORPORATION OF ILLINOIS.

DISCONNECTING SWITCH.

Application filed June 21, 1923. Serial No. 646,750.

My invention relates to disconnecting switches.

In power house and sub-station transmission installations the disconnecting switch is employed for sectionalizing main and branch lines, for disconnecting branch circuits or a section or number of sections of a main or branch line, also for opening the transmission line where it enters the station to disconnect station apparatus and permit repairs and adjustment without danger of injury from the line potential.

While the particular devices which I shall describe hereinafter, in connection with the drawings are especially adapted for indoor service and are shown and described in that connection, it is to be understood that the invention is not limited to the particular embodiments shown. The invention may be embodied in switches for arrangement outside the power house or sub-station as for example upon a tower or pole adjacent the power house or sub-station or upon a frame on top of the station or other support.

An object of my invention is the provision of a positive and quick opening switch of novel, simple, inexpensive and rugged construction.

Another object is the provision of novel switch operating mechanism for imparting a powerful initial force to the blade or switch member to break contact with the terminal or terminals as the case may be and thereafter an increased velocity to secure quick movement of the blade or switch member to full open position.

This aspect of the invention which is particularly useful and advantageous where considerable current must be carried and particularly where relatively high tension current is involved in securing positive opening and minimizing arcing and burning of the blades and terminals is accomplished by providing a switch blade or member the effective length of which decreases as the blade is moved toward open position and an operating arm or member, the effective length of which increases as it is operated to move the blade to open position.

Another object is the provision of a switch adapted to be installed and operated where a limited amount of room or space is available for mounting and operating the switch.

Another object is the provision of a novel and improved switch adapted for operation in gangs or groups with a minimum number of parts and connections and within a minimum space.

Another object is the provision of a switch adapted, when used in groups or gangs, for side by side mounting in alignment with conductors controlled thereby and without an objectionable reduction in the distances between live parts in different lines or different phases.

Another object is the provision of improved adjusting means between the switch operating mechanism and the switch member or switch members as the case may be.

Another object is the provision of an improved switch adapted for gang or group arrangement in switch cells or compartments and a novel operating mechanism for use in connection with such an arrangement.

I have made a number of improvements with reference to the connections between the operating mechanism and the switch member or members and with reference to the mounting of the operating mechanism with respect to the switch member and the switch mounting and also with reference to the application to the switch member or members of the contact breaking and switch opening force.

To apprise those skilled in the art with the construction and operation of my present invention, I shall now describe several embodiments of the invention in connection with the accompanying drawings which form a part of the present specification.

In the drawings:

Figure 1 is a side elevational view of one embodiment of the present invention.

Fig. 2 is a reduced more or less diagrammatic front elevation of the same.

Fig. 3 is an enlarged top plan view of the embodiment shown in Figures 1 and 2.

Fig. 4 is a side elevational view of another embodiment.

Fig. 5 is a front elevational view of the embodiment shown in Figure 4.

Fig. 6 is a side elevational view of another embodiment.

Fig. 7 is a front elevational view of the embodiment shown in Fig. 6.

Fig. 8 is a side elevational view of another embodiment.

Fig. 9 is a rear elevational view of the embodiment shown in Figure 8.

Fig. 10 is a side elevational view partially in section of another embodiment.

Fig. 11 is a front elevational view of the embodiment shown in Figure 10.

Fig. 12 is an enlarged front view of the mounting base of the device shown in Figures 10 and 11 with the supporting insulators, terminals, switch member or blade, and horizontal connecting link removed.

Fig. 13 is a side elevational view of another embodiment.

Fig. 14 is a front view of the embodiment shown in Figure 13.

Fig. 15 is a side elevational view of another embodiment.

Fig. 16 is a horizontal section on line 16-16 of Fig. 15 showing the connection from the switch operating shaft in elevation.

Fig. 17 is horizontal sectional view through an arrangement of switch cells or compartments showing switches and switch operating means embodying my present invention in connection therewith and;

Fig. 18 is a vertical sectional view on line 18-18 of Fig. 17.

The switch illustrated in Figures 1, 2 and 3 is of the three phase gang type of vertical switch, and comprises six switch units, three of said units for example the upper three units 5-5-5 being adapted for connection to one three phase circuit and the other or lower three units 6-6-6 being in such case adapted for connection to a second three phase circuit. Switch units 5 and 6 are mounted on a vertical wall 7 which may be of concrete, brick, asbestos or any other suitable or preferred material such as usual in power house and substation construction. Upper units 5 are arranged in horizontal alignment and lower units 6 are arranged in horizontal alignment parallel to units 5. As shown in Fig. 2 the upper and lower units 5 and 6 are staggered relative each other.

Referring to the side elevation of Fig. 1 where an upper and lower unit is shown more in detail, it will be seen that each upper unit comprises a lower hinge terminal 8 and an upper contact terminal 9, adapted to be connected by a blade or movable switch member 10. In the embodiment illustrated, each of the terminals 8 and 9 consists of a pair of tongues or terminal lugs and each blade 10 comprises two sets of parallel blades

(Fig. 3) adapted for embracing the tongues or terminal lugs of the upper contact terminals 9 and pivoted on the tongues or terminal lugs of lower hinge terminals 8 by pivot bolts 12, suitable spring washers being preferably provided to resiliently press the blades into contact with the sides of the terminals. It will be understood that this construction is merely exemplary and that the switch blade may be of the trussed or any other suitable or preferred type and other forms and arrangement of terminals may be employed. Each lower switch unit comprises similar upper hinge terminals 8, lower contact terminals 9 and blade or pivoted switch members 10.

The bases of switch terminals 8 and 9 are mounted on insulator clamps or fittings 14 which fittings are in turn mounted on the outer ends of supporting insulators 15. The inner ends of insulators 15 are mounted through suitable fittings 16 upon mounting bases or panels 17 which are in turn suitably mounted upon the face of wall 7. Terminals 8 of each upper switch unit 5 are electrically connected into the circuit or phase in which the unit is arranged by leading current carrying bars, busses or leads 18 shown as of circular cross section through insulating bushings 19 mounted in wall 7 and electrically and mechanically connecting said leads 18 to terminal lugs projecting from the bases of terminals 8 as shown diagrammatically in Fig. 1. Connection between the terminal lugs and leads may be had for example by slotting the lugs and securing the leads in the slotted portions of the lugs. Terminals 9 of each upper unit 5 are connected into the circuit by leading conductors 20 through insulating bushings 19 in the top wall or horizontal partition 21 and similarly connecting them to lugs projecting from the bases of terminal 9. Lower units 6 are similarly connected into the circuits or phases in which they are arranged through conductors or leads 22 and 23 lead in through vertical wall 7 and bottom wall or floor 24.

The mechanism for operating the switch units comprises a horizontal shaft 25 rotatably journaled in bearing blocks 26, which blocks 26 are adjustably mounted in supporting channels 27 at the outer ends of supporting arms or brackets 28 mounted at their inner ends upon wall 7 and projecting therefrom. Each of the blades or pivoted switch member 10 of upper and lower units 5 and 6 is connected to operating shaft 25 through an insulating operating link 30. These links 30 each comprise a rod or length of suitable insulation secured at one end in a ferrule or cap 31 and at its opposite end in the socket portion of a ferrule or cap 32. Ferrules 31 have projecting lugs bifurcated as shown in Fig. 2 and the outer ends of arms 34 fixed upon shaft 25 for rotation

therewith are pivoted in these bifurcated ends upon pins 35 which pins may be held in place by means of suitable cotter pins as shown. Ferrules 32 have projecting arms 5 32' (Fig. 3) pivotally connected with a pair of relatively short links 38 and a pair of relatively long links 40 by pins or bolts 41 which project loosely through the adjacent ends of the projecting arms 32' of ferrules 10 32, links 38 and 40 and are secured in place as by means of suitable washers and cotter pins as shown in Fig. 3. The portions of links 38 through which pins 41 loosely extend have bifurcated hub or sleeve portions 15 42 which engage between the projecting arms of ferrules 32 and between said arms and links 40 and properly space and position links 38 and 40 and the arms of ferrule 32 on pin 41 and prevent binding at that point. 20 Links 40 are spaced within their lengths by spacing post 43 and at their inner or wall ends said links 40 are pivoted between lugs 45 projecting from base or panel 17 upon pins 46 which pins may be held in place by 25 cotter pins as shown or otherwise as desired. The inner ends of relatively short links 38 are pivotally connected through pins 48 to the free ends of blades or switch members 10 beyond contact terminals 9. 30 Operating shaft 25 extends through a vertical wall or partition 50 substantially normal to wall 7 and at its outer end said shaft 25 carries an operating arm 51 fixed thereon. Arm 51 has pivotal connection at 52 with 35 an operating rod 53 which rod 53 extends down to a point conveniently accessible from floor 24. At this point operating rod 53 has pivotal connection through a recurved link 54 with an operating lever 55. Link 54 40 is pivotally connected through a pivot pin 56 with a lug projecting from operating lever 55. Operating lever 55 is pivotally supported on a pin 57 mounted in a forked bracket 58 which bracket is in turn mounted 45 or attached to wall 50 as by means of a bracket 58'. When operating handle 55 is in the upper position illustrated, pivotal connection 56 is in the vertical plane of pivot 57 or is thrown past said plane whereby the 50 operating mechanism is locked against accidental opening. In operating lever 55 the same is thrown or swung downward through approximately 180 degrees to the position shown in dotted lines. By this motion pivot 55 55 56 is carried into or past the vertical plane of pivot 57 below said pivot so as to again lock the operating mechanism in its lower position and the switch units in their open position as will be hereinafter apparent. 60 With the switch units closed as shown the operation of this embodiment of the invention is as follows: 65 Operating handle or lever 55 is thrown into dotted line position (Fig. 1). Operating rod 53 is thereby drawn downwardly and common operating shaft 25 is revolved in a counter clockwise direction (Fig. 1). Rotation of arms 34 with shaft 25 draws operating links 30 toward their dotted line positions. Links 38 and 40 form inverted 70 toggle connections between operating links 30 and switch blades or members 10. Such connections are exceptionally strong mechanically and result in the application of an exceptionally strong initial force to the 75 free ends of blades 10 to break contact with terminals 9 and thereafter in an application of increased velocity to said blades to secure quick movement of same to their full open positions. This powerful initial force is the 80 result of the relatively great movement of operating links 30 in securing relative slight movement of blades 10. The multiplying action or increased velocity results from the 85 action of the inverted toggle in tending to straighten out by the continued motion of pivots 41. The powerful initial force overcomes static resistance of the switch and thereby 90 insures positive breaking of contact and the following accelerating motion moves the blades to full open position quickly so that a quick break of the arc is assured. The arrangement of pivots 41 permits a relatively sharp angle of operating links 30 with 95 respect to the switch blade so that the common operating shaft 25 need not be arranged very far forward of the switch blades. The result is a compact arrangement that may be mounted and operated within a minimum 100 amount of space especially with respect to the space forward of the switch blades and forward of the vertical wall supporting the switching apparatus. 105 The adjustable mounting of bearing blocks 26 already referred to comprises a slidable mounting of said blocks in channel supports 27 at the outer ends of brackets 28 between set screws 60 through which set screws 60 110 the positions of blocks 26 may be adjusted forwardly or rearwardly in channel supports 27 as desired. This adjustment permits adjustment of the operating shaft 25 toward or from wall 7 and thereby the operating mechanism without adjusting the 115 separate connections with the switch blades. The point of rotation of shaft 25 at which the switch units are opened and closed may be adjusted by adjusting the position of shaft 25 in this manner and play between shaft 25 and blades 10 may be eliminated or 120 adjusted as desired without adjusting the various operating links themselves or the pivotal connections therebetween. 125 While the illustration and description of Figures 1, 2 and 3 and certain other embodiments to be hereinafter described relates to three phase systems, the invention is equally as applicable to a single or any other number of phases. In the foregoing embodiment 130

- the units 5 and 6 are illustrated and described as opening and closing together. The operating mechanism may be applied to open one set of switch units and close the other and vice versa. The lower units instead of being inverted may be mounted in upright position as are the upper units or all of the switch units may be mounted in inverted position should that be desirable.
- 10 In the embodiment illustrated in Figures 4 and 5 independent operating shafts 65 and 66 are provided for each of the horizontal rows of switch units 67 and 68. As in the embodiment shown in Figures 1, 2 and 3 the upper and lower switch units 67 and 68 which are mounted on vertical wall 69 are staggered relative each other, upper units 67 being arranged in horizontal alignment and lower units 68 arranged in horizontal alignment parallel to units 67.
- 15 In this case each switch unit comprises a lower hinge terminal 70 and an upper contact terminal 71 adapted to be connected by a blade or movable switch member 72. Each 20 of the terminals 70 and 71 consists of a tongue or terminal lug and each blade comprises a pair of parallel blades for embracing the terminal lugs of the contact terminals and pivoted on the tongues or lugs of hinge 25 terminals 70 by pivot bolts 73, suitable spring washers being provided to resiliently press the blades into contact with the sides of the terminals. As before, supporting insulators 30 are mounted at their inner ends upon the face of wall 69 and project therefrom. The outer ends of insulators 74 are provided with fittings 75 upon which terminals 70 and 71 are suitably mounted. Terminals 70 and 71 are electrically connected into the circuits 35 or phases in which the respective units are arranged through conductors or leads 76.
- 40 The horizontal switch operating shafts 65 and 66 are rotatably journaled in bearing blocks 78 which blocks 78 are as before, adjustably mounted in supporting channels 79 at the outer ends of supporting arms or brackets 80 between set screws 82 through which said blocks are adjusted forwardly or rearwardly through channels 79 as desired.
- 45 Supporting arms or brackets 80 are suitably mounted at their inner ends upon wall 69 and project therefrom.
- 50 Each of the blades or pivoted switch members 72 of upper switch units 67 is connected to operating shaft 65 through operating or connecting links 84 and 85. Links 84 are fixed at one end upon shaft 65 for rotation therewith and at their opposite ends said links 84 have pivotal connection at 86 with links 85. The opposite ends of links 85 are pivotally connected at 87 with the free ends of blades 72 outwardly beyond contact terminals 71. The blades 72 of the lower switch units are similarly connected to shaft 66 through links 88 fixed upon said shaft 66

for rotation therewith and having pivotal connection at 89 with links 90 which links 90 are in turn pivotally connected at 91 with blades 72 outwardly beyond contact terminals 71.

Links 84-85 and 88-90 form straight or substantially 180 degree toggle connections between shafts 65 and 66 and the switch blades 72. These connections impart a strong initial opening force to blades 72 upon initial rotation of shafts 65-66 in a clockwise direction to secure a positive breaking of contact and thereafter an increased velocity to secure quick movement of the blades to full open position. This powerful initial force is as before the result of the relatively slight movement of blades 72 which accompanies relatively great initial rotation of shafts 65 and 66. As the pivot ends 86-89 of arms 84-88 move toward a vertical plane through the axis of shaft 65-66, the ratio of the amount of movement of blades 72 to the amount of rotation of shafts 66-67 increases. This results in a multiplying action or increased velocity with a resulting quick movement of the blades to full open positions.

Operation shafts 65 and 66 extend through a vertical wall or partition 92 shown in Fig. 5 but omitted in Fig. 4. Said wall or partition 92 is positioned substantially normal to wall or partition 69. At their outer ends shafts 65 and 66 carry operating arms 93 and 94 fixed thereon. Arm 93 has pivotal connection at 95 with the upper end of a relatively long operating rod 96. Arm 94 has pivotal connection at 97 with the upper end of a relatively short operating rod 98. The lower ends of rods 96 and 98 are pivotally connected through a pin 99 with a pair of lugs 100 projecting from an operating lever 101. Operating lever 101 is pivotally supported on a pin 102 mounted in a bracket 103 which bracket 103 is mounted through an extension 104 upon wall 69. As explained in connection with operating handle 55 when operating handle 101 is in the upper position illustrated, pivotal connections 99 are in the vertical plane of pivot 102 or are swung past said plane whereby the operating mechanism is locked against accidental opening. In operating lever 101 the same is thrown or swung downward through approximately 180 degrees to the position shown in dotted lines. By this motion, pivot pin 99 is carried into or past the vertical plane of pivot 102 below said pivot so as to again lock the operating mechanism in its lower position and the switch units in their open position.

The operating of this embodiment of the invention is as follows:

With the switch units closed and the operating mechanism in the position shown, operating handle lever 101 is thrown into

- dotted line position. Operating rods 96 and 98 are thereby drawn downwardly and operating shafts 65 and 66 are revolved or rotated in clockwise direction (Fig. 4).
- 5 Rotation of arms 84 and 88 with shafts 65 and 66 draws or pulls blades 72 toward open position through links 85 and 90, first with an exceptionally strong force to break contact and thereafter at increased velocity to
- 10 secure quick movement of the blades to full open position.
- This embodiment of the invention is equally as applicable to a single or any other number of phases, and as before while the 15 various units are illustrated and described as opening and closing together it is to be understood that the operating mechanism may be applied to open one set of switch units and close another and vice versa.
- 20 As before, the adjustable mounting of bearing blocks 78 in supporting journals 79 between set screws 82 permits adjustment of the points in the rotation of shafts 65 and 66 at which the switch units are opened and 25 closed and also permits eliminating entirely or independently adjusting as desired any play between either of shafts 65 or 66 and blades 72 without adjusting the various operating links themselves or the pivotal connections therebetween.

The embodiment shown in Figures 6 and 7 is especially suited for use where the amount of space is even more limited or restricted especially the space forward of the 35 supporting wall upon which the switch units are mounted. In this case upper switch units 110 are again shown as mounted in a horizontal row and lower units 111 mounted in a parallel horizontal row and staggered relative to said first units. Each of the switch units comprises a hinge terminal 112 and a contact terminal 113 adapted to be connected by a switch blade 114 which comprises two parallel blades embracing the 40 terminal lugs and pivoted upon the hinge terminal by pivots 115. The usual spring washers resiliently press the two switch blades of each unit into contact with the terminals. Terminals 112 and 113 of each 45 unit are connected into the respective circuits or phases through suitable conductors, leads or busses 116.

The bases of terminals 112 and 113 are mounted on insulator fittings 118 on the 55 outer ends of supporting insulators 120. The inner ends of insulators 120 are supported upon mounting bases 121 which mounting bases 121 are in turn suitably mounted upon vertical wall or partition 122. 60 Mounting bases 121 are of hollow formation and the horizontal switch operating shafts 123 and 124 extend through these bases 121 and are rotatably journaled in suitable bearings associated therewith. Within 65 each base 121 each of the shafts 123 and 124

carries an arm 125 fixed on the shaft for rotation therewith and the opposite ends of each of said arm 125 has pivotal connection at 126 with forwardly extending switch operating links 127. The forward end of 70 each link 127 extends between the parallel blade members of blades 114 and are pivotally connected at 128 therewith as through suitable bolts as shown.

Operating shafts 123 and 124 extend 75 through a vertical wall or partition 130 substantially normal to wall or partition 122 and at their outer ends each of said shafts carries an operating arm 131 fixed thereon for rotation therewith. Arms 131 have 80 pivotal connection at 135 with the upper ends of operating rods 136, the lower ends of which rods 136 are pivotally connected through a pin 137 with lugs 138 projecting from an operating lever 140. As before, 85 lever 140 is pivoted on a pin 141 mounted in a bracket 142 which bracket is in turn mounted upon wall 122, and as before pin 137 is in the vertical plane of pivot 141 or is thrown past said plane when lever 140 is 90 thrown into its lower position to open the switch as well as when said lever is in its upper position and the switch closed as shown. The switch units and operating mechanism are thereby locked in each position. 95

From the foregoing it is now apparent that when lever 140 is swung into dotted line position (Fig. 6) operating rods 136 are drawn downwardly and shafts 123 and 124 are revolved in a counter clockwise direction. The accompanying rotation of arms 125 moves operating links 127 outwardly through openings 145 in the front walls of bases 121 and forces blades 114 into open 100 position about their pivots 115. The arrangement of the operating mechanism between the supporting wall and the switch blades eliminates all mechanism outwardly beyond said blades and minimizes the 105 amount of space required to mount and operate the switch. As in the embodiments already described and the embodiments to be hereinafter described units may be employed separately or in group, either unit 110 may be inverted without change, or the operating mechanism may be applied to open one set of switch units and close the other.

The embodiment illustrated in Figures 8 120 and 9 is especially adapted for use where the space forward of the supporting wall 150 is limited or restricted and space on the other side of said wall 150 as in the next or adjacent room is available for the operating 125 mechanism. In this case a group or gang of three switch units is shown. The novel aspects of this embodiment may be embodied in a system employing a single or any other number of switch units. In this case mount- 130

ing bases or panels 151 which support insulators 152 and from which said insulators project are mounted upon one side of wall 150. Fittings 153 on the outer ends of 5 insulators 152 carry the contact and pivot terminals 155 and 156 of the switch unit which terminals are adapted to be connected by blades 158 pivoted by bolts 160 upon the hinge terminals 156 and adapted to be swung 10 into and out of electrical engagement with contact terminals 155. As before suitable spring washers are preferably provided to resiliently press the blades into contact with the sides of the terminals, and said terminals 15 are connected to the circuits or phases through busses or leads 162 formed, in this case, of strips or bars of oblong cross section.

The horizontal switch operating shaft 165 is arranged on the opposite side of wall 20 or partition 150, for example in an adjacent room or compartment of the power house or sub-station being rotatably journaled in bearing brackets 166 which may be mounted upon wall 150 through some of the bolts or 25 other securing means through which bases 151 on the opposite side of the wall are mounted. Arms 168 fixed upon shaft 165 in the bifurcated or forked ends of the bearing arms of brackets 166 have pivotal connection at their opposite ends at 170 with 30 operating links 172 which links 172 project forwardly through openings 173 in wall or partition 150 and base 151 and are pivotally secured at their forward ends between the 35 pairs of blade members of blades 158 as shown at 174.

Fixed upon shaft 165 adjacent intermediate bearing bracket 166 is an operating arm 176 having pivotal connection at 178 40 with an operating rod 180 which rod 180 extends down to a point conveniently acceptable from the floor of the room or compartment for example. At this point rod 180 has pivotal connection through a recurved 45 link 181 with an operating lever 182. Operating lever 182 is pivotally supported on a pin 184 mounted in a bracket 185 which bracket is in turn mounted or attached to wall 150. Link 181 is pivotally connected 50 through a pivot pin 186 with a lug 187 projecting from operating lever 182. When operating lever 182 is in the upper position illustrated, pivotal connection 186 is in the vertical plane of pivot 184 or is thrown past 55 said plane whereby the operating mechanism and switch units are locked against opening.

When the lever is swung into its lower dotted line position pivot 186 is again positioned in or thrown past the vertical plane of 60 pivot 184 to lock the switch unit and operating mechanism in open position. The operating mechanism may be additionally locked by providing lever 182 with lugs 190 having apertures adapted to register with an aper-

ture 191 in bracket 185 in the two positions 65 of the lever so that a locking pin may be inserted through said registering apertures.

With the switch units in closed position as shown opening is had by swinging or throwing lever 182 from its full line to its dotted 70 line position (Fig. 8). Operating shaft 165 is thereby rotated in a clockwise direction, forcing operating links 172 forwardly. This forward movement of links 172 forces or pushes blades 158 through pivotal connections 174 outwardly into open position. In closing lever 182 is swung into its full line position, drawing or pulling blades 158 about pivots 160 into engagement with contact terminals 155. 75

In Figures 10, 11 and 12, I have shown another embodiment of the invention in a switch unit which may be used alone or in any desired group or gang arrangement. In this case, hinge and contact terminals 200 and 201 are carried by fittings 202 mounted upon the outer ends of supporting insulators 203. The inner ends of insulators 203 are mounted in base fittings 204 which fittings are mounted through bolts 205 upon a 80 mounting base 206 and the mounting base 206 is in turn attached to wall, partition or other support 207 as by means of bolts 208. Terminals 200 and 201 are connected into the line or circuit through busses 210 each of 85 which is shown as comprising a plurality of flat strips or bars. A pivoted blade 212 is provided for connecting and disconnecting terminals 200 and 201. 90

Blade 212 comprises two sets of parallel 100 blades (Fig. 11) adapted for embracing a pair of tongues or terminal lugs projecting from contact terminal 201 and pivoted on a pair of tongues or terminal lugs projecting from hinge terminal 200 by pivot bolts 214. 105 Spring washers press the blades into contact with the sides of the terminals. 110

The forward end of an operating link 216 is pivoted between the two intermediate blade members of blade 212 upon a pin 218 secured in said blade members. Operating link 216 extends back through an opening 220 in the front wall of hollow mounting base 206 and into a recess 221 in wall or support 207 where it is pivotally connected at 222 in the forked end of an arm 224 fixed upon operating shaft 225 for rotation therewith. Forward end of link 216 has a head 226 having threaded engagement with link 216 through which adjustment between pivots 218 and 222 is secured. Shaft 225 is rotatably journaled in web portions 228 of mounting base 206 and fixed upon said shaft is an arm 230 having pivotal connection at 231 (Fig. 10) with a downwardly extending operating rod 232. Rod 232 extends to the point from which the switch is operated and is there connected with suitable operating means 120 125

such as any of those previously described. for example.

The foregoing switch gives a positive, quick break and by reason of its compactness requires very little mounting and operating space. It is especially adapted for use where the space or room forward of the supporting wall is limited or restricted and where there is no space available on the other side of said wall for the operating mechanism.

In Figures 13 and 14, I have shown a single switch unit similar to the units employed in the gang or group arrangement of Figures 6 and 7. In this case, however, hinge terminal 250 and contact terminal 251 each has a pair of tongues or lugs projecting forwardly therefrom and blade 252 comprises two sets of parallel blade members adapted for embracing the tongues or lugs of the contact terminal and pivoted on the tongues or lugs of the hinge terminal by a pivot bolt 253. As before, the free ends of the blades are clamped together by bolts 254 and resiliently pressed into contact with the sides of the lugs or tongues of terminal 251 by spring washers 255. Spring washers 256 press the hinge ends of the blade member against the lugs or tongues of hinge terminal 250. Suitable sleeve or other spacing means may be provided for properly spacing the respective blade members.

Terminals 250 and 251 are connected into circuit through busses 260 and said terminals are supported upon the outer ends of insulators 261 which insulators are carried by and project from hollow mounting base 262. Shaft 263 rotatably journaled in base 262 and operated through rod 264 and arm 265 is connected through arm 266 and link 267 with blade 252, the forward end of said link 267 projecting between the intermediate blade members of blade 252 and being pivotally mounted upon a bolt or pin 270 secured in said blade members.

The embodiment shown in Figures 15 and 16 is also especially suited for use where the amount of space or room for mounting and operation is limited and space on the other side of the supporting wall is not available for the operating mechanism. In this case supporting insulators 270 are mounted upon and project from the front of a mounting box 271 which is mounted in wall 272 with its front and rear sides flush with the opposite sides of said wall. Box 271 is preferably a cast iron box having front and rear retention flanges 274 and 275 and internal lugs 276 for carrying a rear cover 278 flush with the rear of the box. Cover 278 may be secured to lugs 276 as by means of small machine screws as shown.

Operating shafts 280 extends through and is housed in conduit or tubing sections 281

which extend through wall 272 and are secured by threaded engagement in bosses 283 formed integral with and projecting from opposite sides of box 271.

Fixed upon shaft 280 within box 271 is a forked arm 286, the forked end of which has pivotal connection through a pin 288 with a forwardly extending operating link 287. Link 287 projects forwardly through opening 290 in the front wall of box 271 and has pivotal connection at 291 with switch blade 292. Blade 292 is pivoted at 293 to hinge terminal 294 and is adapted for cooperation at its opposite end with contact terminal 295. Terminals 294 and 295 are connected into circuit through busses 296. An arm 297 fixed upon shaft 280 beyond one end of wall 272 or at any other desired point, is pivotally connected at 298 with a downwardly extending operating rod 299. Where it is desired to fix arm 297 on shaft 280 within the length of the wall an opening or recess in the wall to permit the arm to project therefrom may be provided.

In operation rod 299 is drawn downwardly as by means of suitable operating means (not shown) at the lower end thereof with a resulting counter clockwise rotation of shaft 280. Rotation of arm 286 with shaft 280 forces blade 292 positively and quickly to open position through link 287. To close the switch, shaft 280 is rotated in the opposite direction by rod 299 and blade 292 is drawn or pulled through link 287 about its pivot 293 into electrical engagement with contact terminal 295.

The foregoing switch is opened quickly and positively. There is no operating mechanism outwardly beyond the switch blade and the space between the blade and wall is minimized by the mounting of the operating shaft and connections within the wall.

In Figures 17 and 18, I have shown the embodiment of Figures 4 and 5 mounted in parallel vertical compartments or switch cells 350. Cells or compartments 350 are defined by vertical partitions 352 and a back wall 353 upon which wall 353 the switch units are mounted in vertical aligned pairs. Each switch unit of which there is an upper unit 354 and a vertically aligned lower unit 355 in each compartment, comprises hinged and compact terminals 360 and 361 adapted to be connected by a blade or movable switch member 362. Each terminal has a tongue or terminal lug and each blade comprises a pair of blade members for embracing the terminal lugs of the contact terminals and pivoted to the tongues or lugs of the hinge terminals by bolts 365, suitable spring washers being provided as before. Terminals 360 and 361 are mounted on fittings 366 on the outer ends of insulators 367. The inner ends

of insulators 367 are mounted through suitable bases or fittings upon wall 353. Terminals 360 and 361 are connected into circuit through conductors, busses or leads 370.

5 Horizontal switch operating shafts 375 and 376 extend through the cells or compartments 350 and the partitions defining same and are rotatably journaled in bearing blocks 378. Bearing blocks 378 are 10 mounted in vertical partitions 352 with their outer surfaces flush with the outer edges of said partitions. The blades of the upper switch units are connected to operating shaft 375 through links 380 and 381. Links 380 15 are fixed at one end upon shaft 375 for rotation therewith and at their opposite ends have pivotal connection at 382 with links 380. Links 380 extend between the free ends of blades 362 outwardly beyond contact terminals 361 and are pivotally connected with the blades at that point. Blades 362 of the 20 lower units are similarly connected to shaft 376 through links 384 and 385.

Operating shaft 375 and 376 project outwardly through end wall 386 (Fig. 17) and at their outer ends carry arms 387 and 388 fixed thereon. Arm 387 has pivotal connection at 390 with an operating link or rod 391 which may comprise a length of insulation 25 or be otherwise formed as in the other embodiments. The opposite end of link or rod 391 has pivotal connection with arm 388 at 392 and at 392 arm 388 also has pivotal connection with a second rod or link 393. The 30 lower end of link 393 is pivotally connected at 394 with lug 395 of operating lever 396. Lever 396 is pivotally supported on a pin 397 mounted in a bracket 398 which bracket is in turn mounted through a bracket 400 35 upon the outer surface of end wall 386. Compartments or cells 350 are closed by a cover or door 405.

In operation lever 396 is swung from its full to its dotted line position, drawing or 40 pulling link 393 downwardly with a resulting counter clockwise rotation of shaft 376 and corresponding counter clockwise rotation of shaft 375 through link 391. Rotation of arms 380 and 384 with shafts 375 and 376 draws or pulls blades 362 into open position through links 381 and 385 first with a strong force to positively break contact and then at increased velocity secure quick movement to full open position. Shafts 375 and 50 376 may each be connected directly to lever 396 as in the other embodiments or the connection shown in Figures 17 and 18 may be employed in the other embodiments as desired. The provision for securing a strong 55 initial opening force followed by an increased velocity in a cell or compartment of minimum size and in so simple a manner is a highly important aspect of my invention.

As has already been pointed out a highly 60 important aspect of the invention is the in-

creasing effective length of the operating arm and the decreasing effective length of the switch arm or member in moving same to open position. This will be readily apparent upon reference to Figures 10 and 11 70 for example. In that embodiment when shaft 225 is rotated by rod 232 in opening the switch, arm 224 moves toward a vertical plane through its axis with a resulting increase in its effective length from initial 75 effective length A to effective length B. At the same time as the switch blade or member 212 moves toward open position its effective length decreases from initial effective 80 length C when in closed position to effective length D and even further if the blade is moved further from contact 201.

I refer to the vertical plane through the axis of arm 224 simply as convenient in describing the particular arrangement shown. 85 The switches of my invention may of course be mounted horizontally or otherwise as desired in which case this term would vary.

In the embodiment shown in Figures 1, 2 and 3 as the switch is opened the effective 90 length of the switch members decrease while the effective lengths of arms 34 increase.

In the embodiment shown in Figures 4 and 5 as blades 72 are moved toward open 95 position their effective length decrease while the effective lengths of arms 84 and 88 increase. The same results are secured in the other embodiments.

I do not intend to be limited to the precise details illustrated and described.

I claim:

1. In a switch, a first element, a movable switch member pivotally connected to said element, a second element adapted to be engaged by the said switch member, and link mechanism connected to said switch member nearer to the second element than the first and operable on said switch member at only a single point throughout its entire range of movement for causing a strong initial force to be applied to separate the switch member from the second element and for thereafter moving the switch member away from the second element with an increasing velocity, the effective length of the said switch member being at a maximum when it is engaged with said second element and constantly decreasing as it is moved away from the second element. 110

2. In combination, a pair of switch terminals, a switch blade for connecting the said terminals, said blade being pivoted at one end to one of said terminals, an element located intermediate the said switch terminals and connected at its outer end directly to only a single point on the said switch blade, a shaft, a member connected at one end to the said shaft and pivotally connected at its other end to the inner end of the said 125 130

- element, and means for actuating the said shaft to cause the said element to be reciprocated.
3. In combination, a pair of switch terminals, a support for the said terminals, a switch blade for connecting the said terminals, said blade being pivoted to one of said terminals, a shaft supported by the said switch terminal support, an element positioned intermediate the switch terminals and pivotally connected at one end directly to only a single point on the said switch blade for moving the said switch blade into closed and open positions, a link connected at one end 10 to the said shaft and pivotally attached at its free end to the other end of the said element, and means for actuating the said shaft to cause the said element to be reciprocated.
4. In combination, a support, a pair of switch terminals mounted on the said support, a switch blade for connecting the said switch terminals, the said blade being pivoted at one end to one of the said terminals, 20 an element pivotally secured at one end to the said switch blade and extending inwardly from the said blade intermediate the said switch terminals, the said element being operatively connected to the said switch blade by only its pivot, the said element being adapted to move the switch blade into and out of connection with one of the said switch terminals, a shaft suitably supported by the said support, means connecting the inner end of the said element with the said shaft, and means for actuating the said shaft to cause the said element to be reciprocated.
5. In combination, a support, a pair of switch terminals mounted on the said support, a switch blade for connecting the said switch terminals, the said blade being pivoted at one end to one of the terminals, an element pivoted at one end directly to an 40 edge of the said switch blade and extending inwardly from the said blade intermediate the said switch terminals, a shaft carried by the said support, a toggle link arrangement rigidly attached to said shaft, the free end of one of the links comprising the said arrangement being pivotally connected to the inner end of the said element, and a rod pivotally attached at one end to the free end of another link of the said arrangement.
6. In combination, a plurality of switches, a common support for the said switches, each switch comprising a pair of switch terminals connected by a switch blade, one end of the said blade being pivotally connected 50 to one of the terminals, an element pivotally attached at one end directly to the said switch blade and projecting inwardly intermediate the said switch terminals towards the support, and toggle link mechanism associated with the other end of the said ele-
- ment, and a common shaft for all of the said switches for actuating the link mechanism of each switch to cause the associated switch blades to be moved into and out of a closed position.
7. In combination, a plurality of switches, a common support for the said switches, each switch comprising a pair of switch terminals, a switch blade for connecting the said terminals, one end of the said switch blade 70 being pivoted to one of the terminals, an element pivoted at one end directly to the said switch blade and projecting inwardly intermediate the said switch terminals towards the said support, a shaft, a link secured to the inward end of the said element and connecting the said element to the shaft, and means for operating the said shaft, the said shaft operating all of the said switches.
8. In combination, a support, a pair of spaced switch terminals mounted on the said support, a switch blade for connecting the said terminals, the said blade being pivoted at one end to one of the terminals, an 80 element pivoted at one end directly to the said switch blade and projecting inwardly towards the said support intermediate the spaced switch terminals, a link pivotally secured at one end to the inward end of the said element, a shaft to which the other end of the said link is connected, a second link rigidly secured at one end to the said shaft, a rod pivotally attached at one end to the free end of the said second link, and lever- 90 age mechanism for actuating the said rod.
9. In combination, a pair of spaced switch terminals, a support for the said terminals, a switch blade for connecting the said terminals, one end of the said blade being pivotally attached to one of the terminals, an element pivotally attached at one end to the said switch blade and projecting inwardly intermediate the said spaced switch element towards the said support, the other end of the said element being positioned 100 inside of the said support, a shaft mounted inside of the said support, a rod mounted external of the said support, toggle mechanism secured to the said shaft for connecting one end of the said rod with the inner end of the said element, and means for actuating the said rod.
10. In combination, a pair of switch terminals, a support for the said terminals, a switch blade for connecting said terminals, one of the ends of the said switch blade being pivotally attached to one of the said terminals, an element pivotally attached at one end to the said switch blade intermediate its ends, said element projecting inwardly into the said support, a shaft mounted entirely within the said support, a link also mounted entirely within the said support rigidly secured at one end to the said shaft, 110 the free end of the said link being pivotally 115
- 120
- 125
- 130

attached to the inner end of the said element inside of the said support, a second link rigidly secured at one end to the said shaft and projecting outwardly from the said support, a rod located entirely externally of the said support and pivotally attached at its upper end to the free end of the second link, and leverage mechanism associated with the

other end of the said rod externally of the said support for actuating the said rod to cause the said element to move the said switch blade into open and closed positions.

In witness whereof, I hereunto subscribe my name this 18th day of June, 1923.

CHRISTEN CHRISTENSEN.
